CHIROPRACTIC ADJUSTING TABLE

Henry E. Saak, Maplewood, Mo.

Application July 29, 1936, Serial No. 93,189

5 Claims. (Cl. 128—73)

The object of my invention is to make a table to be used by chiropractors in making spinal adjustments. Among many more specific objects is to devise a table which will be convenient and comfortable for the patient and efficient for the operator. A patient, in order to secure a spinal adjustment and other treatments from the chiropractor must lie flat, face downward on the table. The head, chest and feet are supported on pads or cushions which cushions must be adjustable so as to raise or lower the head, chest and feet selectively and independently. These cushions must be so positioned on the table that they may be slid longitudinally relative the table and means must be provided to secure them in any selected position. The table must be so mounted that it may be rotated in a horizontal plane, either clockwise or anticlockwise through 360 degrees, means must be provided for selectively raising or lowering the table when a patient is lying on the table with a minimum of effort on the part of the operator. The table must be so constructed that it may be tilted to a position substantially vertical so that a patient may stand on a step at the lower table end, when tilted, with his face toward the table, and leaning against the table, so that the operator may easily rotate the table on its support to a horizontal or any intermediate position. This operation is accomplished by means of simple controls for the operator; there being one control on each side of the table. Obviously, when the table is in a horizontal position, with a patient lying on it, the patient will be lying face downward, exposing his spine to the operator. All the means necessary to accomplish these ends are herein described.

Additional specific objects consist in supplying hydraulic means for raising or lowering the table and hydraulic means for tilting or rotating the table, the controls for which means are simple levers which may be operated by the flick of a finger. Both these hydraulic means are operated by one electric motor and fluid pump. The same fluid is used by both hydraulic means. A simple two-way valve controls the fluid flow from one hydraulic means to the other. By these means, the structure will accomplish the results intended. The table is made "foolproof" to a degree not heretofore accomplished because the table cannot be tilted when in its elevated position, because the hydraulic tilting means cannot operate in this position, since the fluid medium for tilting is being used in the hydraulic elevating means and because the two-way valve pre-

vents the fluid from passing to the tilting means when the table is in its elevated position.

Furthermore, a jack preferably of the hydraulic type such as used in lifting automobiles for tire repairs, is employed to easily raise and lower cushions on the table. The weight of the patient's body supported by the cushions may be easily raised or lowered thereby. A bifurcated head cushion is used in order to support the patient's head on the forehead and permit the nose and mouth to extend into the space between the bifurcated portions and permits the patient's cheeks to rest on the bifurcated portions.

With these and other objects in view, my invention has relation to certain novel features of construction and arrangement of parts, which will be hereinafter more fully described and pointed out in the claims and illustrated in the drawings in which:

Fig. 1 is a plan view of the device, the table being shown in horizontal position.

Fig. 2 is a side elevation thereof, the broken lines indicating moved positions of the various cushions.

Fig. 3 is a left end view of Fig. 2.

Fig. 4 is a view in vertical section, the table top being shown in tilted position.

Fig. 5 is a similar view with the left-end portion of the table top being shown broken away, the table being again shown in horizontal position but elevated vertically from its Fig. 2 position.

Fig. 6 is an enlarged fragmentary sectional view similar to Fig. 4, illustrating in more detail the region surrounding the pumps and valve mechanism.

Fig. 7 is a similar view corresponding to the Fig. 5 position of said parts.

Fig. 8 is a vertical section on the line 8—8 of Fig. 4 and illustrates the valve setting for the forward movement of the horizontal piston.

Fig. 9 is a like view illustrating the valve setting for the return of the horizontal piston.

Fig. 10 is a vertical section on line 10—10 of Fig. 9.

Fig. 11 is a sectional view taken on line 11—11 of Fig. 4.

Fig. 12 is an enlarged central section through a portion of the left end head rest cushion carrier, showing the means of changing its position and locking it in place.

Fig. 13 is a sectional view on line 13—13 of Fig. 2.

The numeral 14 designates as a whole my improved chiropractic adjusting table top support

and table top, which as will be seen, may be rotated as a unit about its center throughout 360 degrees, and may be tilted to various positions, and can be elevated vertically, as desired.

5 The table top proper indicated as 15 is composed of two side frame channel members 16 tied together at one end by a cross bar and tie rods designated as 17, and at the opposite end by a foot rest 18, as shown. The patient stands 10 upon the foot rest 18, when the table is in its Fig. 4 position, as will be described more fully, hereinafter.

15 Numeral 19 designates a circumferential base plate, to which is affixed a vertical pedestal 20, which is in the form of a cylinder. Bolted or otherwise fixed to the inturned flanges of a hollow piston 21 is a casting 22 generally cylindrical in contour, except at its left end where a depending horizontal extension 23 thereof supports 25 a motor 24. Numeral 25 designates a cord to be plugged into a wall socket for furnishing current to the motor 24. Numeral 26 designates a hand switch also attached to the end of a cord, which cord is connected to said motor 24, whereby the operator can stop and start the motor at will. Details of the switch, motor, etc. are not shown since they are well known.

30 Numeral 27 indicates the motor shaft, which is joined by a universal coupling 28 to the drive shaft 29 of a suitable pump 30, mounted within a portion of casting 22, as shown in the drawings. It is deemed unnecessary to illustrate or describe the details of the pump, as the pump is conventional. To the intake side of the pump 35 30 is fixed a vertical pipe 31, which extends to within a slight distance of the bottom 32 of the hollow piston 21. The output side of the pump leads by means of pipe 33 to a two-way valve 34, which controls the movements of the table top 40 support and table top. Numeral 35 indicates a pipe, which leads from said valve into the cylinder portion 36 of casting 22, in which portion a hollow piston 37, as will be described, serves to 45 tilt or rotate the table top to any desired angle between the horizontal and that shown in Fig. 4, which illustrates the extreme right position of said piston.

50 At 38 is shown a short down-turned pipe, and at 39 a long vertical pipe, both of which also extend from the valve 34, as clearly illustrated in Figs. 6 and 7. The pipe 39 extends through the bottom of cylinder 21 and is in communication with oil chamber 40 formed by the pedestal support 20.

55 A predetermined amount of oil is, of course, present in the combined vertical and horizontal piston arrangement. An inspection of Figs. 6 and 7 will show the location of said oil under certain conditions. In Fig. 6 the oil is being pumped from the piston 21 into the cylinder 36 (as indicated by the arrows) forcing piston 37 to the right. In Fig. 7, as indicated by the broken arrows, the oil has been exhausted from the cylinder 36 back into the piston 21, and is 60 being pumped from said cylinder 21 into chamber 43 causing cylinder 21 to rise.

65 In the Fig. 2 position of the table top practically all of the oil is contained in cylinder 21. The description will follow later covering the 70 operation of the device, which will clarify these movements.

75 Numeral 41 designates a cross pivot pin, which extends from one side of frame 16 to the other, and supports one end of the table top by means of brackets 42 depending therefrom, the pin pass-

ing through the side walls of casting 22. Said casting 22, it will be seen, therefore, constitutes the main support for the table top, since a pair of integral lugs 43, formed on the table top support (see Figs. 2, 8 and 9), and which extend laterally also support the other end of the table top on the table top support, when in horizontal position.

80 Numerals 44 designates a roller with ball bearings mounted on a transverse pin fixed in a pair of integral upstanding ears formed on the piston 37. A cross-plate 45, welded or otherwise fixed to the table top frame 15, has a depending arm 45a pivoted on the cross pin 41. The roller engaging edge 46 of this arm terminates in a hook portion 47, see Figs. 4 and 5. When the table top is in its extreme tilted position, the hook portion 47 partially encircles the roller 44 stabilizing the table top in this position.

85 Referring now to Figs. 8, 9 and 10 particularly, a novel feature of this invention is the simple and efficient method employed to set the valve for raising and lowering the lift and tilting the table top. A pair of bifurcated arms 48 and 49 are pivotally mounted on stud 50, fixed in a vertical wall portion 51 of the casting 22. For convenience of manipulation each arm has affixed thereto, at its outer end, a knob 52. The upper fork 53 of arm 48 is provided on its lower edge with a predetermined number of rack teeth 54, which mesh with a pinion 55 fixed to a horizontal shaft 56 extending through wall 51. As shown at 57, the other fork is offset near the pivot 50, in order that the said upper fork 53 may be aligned with fork 58 of arm 49. The latter is provided along its upper edge with a rack 59 comprising the same number of teeth as carried by the fork 53, likewise meshing with said pinion 55.

90 Numeral 60 designates a comparatively heavy coil spring interposed between the wall 51 and the lower extremities of the arms 48 and 49, the spring surrounding the stud as shown. The function of said spring is to maintain the arms in their Fig. 8 or raised, as well as in their Fig. 9 or lowered position, as desired. It is obvious that either the arm 48 or the arm 49 may be dispensed with. However, provision of a pair of such arms enables the operator to manipulate the valve from either side of the table, which 95 is a distinct advantage. It is, of course, apparent that the arms always move together, regardless of which knob 52 is raised or depressed.

100 Any suitable stop or stops may be employed to limit the upward and downward stroke of the arms. The drawings indicate the downward movement as being limited by the edges of extension 23 of casting 22, and the upward movement by the contour of the upper forks as indicated at numeral 61.

105 Referring now more particularly to Figs. 6, 7 and 11, it will be seen that the valve 34 is mounted with its core at right angles to the horizontal center line of the piston 36. It is also seen that it is a simple two-way valve, since but two 110 settings thereof are required. Mounted on the extension 62 of the valve core is a bevel gear 63 in mesh with a similar gear fixed to the shaft 56, hereinbefore mentioned.

115 By this arrangement raising or lowering the arms 48 or 49 will rotate the valve core approximately 90 degrees to the right or to the left, as viewed in Figs. 6 and 7 of the drawings. It is understood, of course, that this particular arrangement is not to be considered limiting, since 120 75

I have found in actual practice that the valve 34 may be mounted in a plane parallel with the center line of the piston 36. In that case the bevel gearing may be entirely dispensed with, shaft 56 being directly connected with core stem 62, which would then be in alignment therewith. In the latter event, of course, the parts 48 to 61, inclusive remain as illustrated.

Numerals 64 designates a removable cover plate closing an opening in the casting 22, permitting inspection of the pump, valve, etc., and for replenishing the oil, if necessary. Although omitted in the drawings for the sake of clarity, an inverted U-shaped hood of thin metal may be placed over the entire casting 22, with necessary openings or slots therein for the arms 48 and 49, ears 43 and the arm 45a. At 65 are shown a pair of handles mounted on the side frames 16 for the convenience of the patient. Referring now to Figs. 1 to 5, there is indicated at 66 a carriage, which supports a bifurcated head rest or cushion 67 and a chest rest or cushion 68. A similar carriage 69 has mounted thereon a weight supporting cushion 70, and a knee flexer or cushion 71.

Each carriage comprises a channel shaped base 72 of a width slightly less than the transverse distance between the inner opposing faces of the channel shaped side frame members. Ball bearing rollers 73 are mounted in the depending flanges of the carriage bases 72, and extend into the channel shaped side members 16, riding between the upper and lower flanges of said channels. Welded or otherwise secured to each base 35 is a housing 72a containing a pinion 74 fixed to cross shaft 75 journaled in the opposite sides of said housing. This pinion may be rotated in either direction by either of two handles 76, one of which is coupled to the shaft 75 at each end. 40: The handles 76 are again in duplicate for each carriage, so that the pinions 74 may be rotated from either side of the table.

Numerals 77 designates a rack bar, extending along the center line of the table top, and fixed 45 in any suitable manner to the cross brace 17 at one end, and at the other to the cross plate 45. As shown more clearly in Fig. 12, the rack bar is below the web portions of the carriage bases 72. Therefore, an opening 78 is formed in each base below 50 the housing 72a through which the pinions 74 extend, and mesh with the stationary rack bar 77. It is obvious that rotation of the shaft 75, by means of the handles 76, will move the carriage, riding on the rollers 73, laterally into various positions as desired. Fig. 2 indicates in broken lines 55 an extreme right position of the carriages.

In order to lock each carriage in any position, a second handle 79 is fixed to each end of the cross shafts 80, also journaled in the sides of the 60 housings 75a. Above the rack, but spaced away from each pinion, there is fixed to each shaft 80 a dog 81 provided with teeth, which cooperates with the rack teeth to lock the carriage in place. To release the carriage, the operator depresses 65 the handle 79 to disengage the dog 81, before manipulating the handles 76.

The cushion 68 is mounted upon a standard 62 secured to base 72. The head rest 67 is pivoted at 63 on said standard, and may be raised or lowered relative to the table top. Means for accomplishing this is designated generally at 84. Pivotedly connected to a lug on the housing 75a is an externally threaded rod 85, which works in an internally threaded tube 86, provided with a 70 handle 87 for manual operation. The tube 86 has

an integral collar 88 thereon, which works against the underside of a collar 89, mounted in extensions 90, of the supporting frame 91 of the head rest cushion as shown in Figs. 2 and 13. By the arrangement described, manipulation of the handle 87 will cause lowering or raising of the head rest as required.

A novel feature of this invention resides in the construction of the head rest cushion per se. A patient lying face downward on a table heretofore found the head rest disagreeably uncomfortable. Constructed in the general shape of a rectangle, such a head rest covers the patient's entire countenance, makes breathing difficult, if not almost impossible, and is generally unsatisfactory.

An inspection of Figs. 1 and 4 will show that the present embodiment overcomes these objections. By constructing the cushion as shown, the two branches 92 and 93 form an opening 94 therebetween, of a size to accommodate the average person's nose, eyes and mouth. The forehead of the patient reposes on the portion of the cushion designated 67a, his chest upon the cushion 68, and the remainder of his body on the cushions 70 and 71. It is readily apparent that with this arrangement, a patient can breathe in comfort and relax while being treated. A jack 95, of any suitable type, is mounted on the carriage 69 for raising and lowering the cushion 70, said jack being provided with an accessible handle 96 for this purpose. The supporting frame 97 of said cushion is mounted on two standards 98 fixed to the side frames 16, said frame pivoting about pins 99 as shown. Pivotally connected to an ear on the frame 97 is the supporting frame 100 of the knee flexer cushion 71. Secured to the underside of the frame 100 are a pair of curved runners 101, which ride along the top surfaces of the side frame members 16. A comparison of Figs. 4 and 5 will suffice to understand the operation of the knee flexer.

The operation of the device is as follows:

Assume that the table top is horizontal and in its lowered position, as shown in Fig. 2, and 45 that the plug on the end of cord 25 has been inserted in a wall socket, thereby furnishing current to the motor. The patient to be treated lies prone on the cushions. The arms 48 and 49 are in the position illustrated in Fig. 2 and the 50 control valve is in the corresponding Fig. 7 position. Practically all of the oil, however, is in cylinder 21, the piston 37 is at the extreme left, the motor, and, therefore, the pump are not in operation. The operator can revolve the table 55 top laterally 360 degrees, although in practice this is never done. The various cushions, of course, have been adjusted as required. This phase of the operation has been gone into fully heretofore, and it is deemed unnecessary to elaborate thereon. In order to elevate the table to the position shown in Fig. 5, the operator merely presses the button on the hand switch 26, which starts the motor and consequently the pump. The fluid is now drawn from the cylinder 21 60 through intake pipe 31, through the pump into valve 34, by means of pipe 33, through the valve and into pipe 39, thence into chamber 40 causing the piston 24 to lift the table top slowly. The capacity of chamber 40 is considerably 65 greater than that of reservoir 21, obviating any danger of elevating the piston too high. The table top may, of course, be positioned at any desired height between the upper and lower extremes, by again manipulating the hand switch 70 75

26 to shut off the motor and pump, thereby arresting further upward movement of piston 21.

To permit lowering of the lift to its Fig. 2 position, the arms 48 and 49 are now raised to their Fig. 8 position, the valve assuming the corresponding Fig. 6 position. The weight of the table top, plus that of the patient thereon, now forces the fluid beneath piston 21 in chamber 40 to rise in pipe 39, thence it goes through valve 10 34 and out pipe 38, returning into cylinder 21.

If it is now desired to tilt the table with the patient thereon to the Fig. 4 position, no change is made in the valve arrangement from that just described. In other words the Fig. 8 position of arms 48 and 49 is not disturbed, and, therefore, valve 34 remains in its Fig. 6 position. The operator manipulates the hand switch 26 to start the motor and pump. The fluid in cylinder 21 is now drawn through pipe 31, pump 30, 20 pipe 33, valve 34, pipe 35 and into the cylinder 36, forcing piston 37 to the right. Roller 44 mounted on said piston rides along the edge of arm 45a slowly raising the table top, as is apparent. The table may be halted at any intermediate angle by means of the hand switch. The patient during this operation stands upon the foot rest or step 18 and grasps the handles 65. The table top is returned to its horizontal position as follows:

30 The handles 48 and 49 are depressed to their Fig. 9 position. The valve again assumes the position illustrated in Fig. 7. The weight of the table top, plus that of the patient now slowly forces the piston 37 to the left, the fluid in cylinder 36 draining through pipe 35, valve 34 and pipe 38 back into the reservoir 21. While the drawings illustrate the preferred embodiment of my invention, I do not wish to be limited to the exact details shown, as numerous changes might 40 be made without departing from the scope of this invention.

What I claim and mean to secure by Letters Patent is:

1. In combination with a pedestal, a table top support secured thereon, a table top hingedly secured to said table top support, a table top frame secured to said table top, a hydraulic piston secured in said table top support and means for supplying hydraulic pressure behind said piston, a roller mounted on a pin fixed in ears formed on said piston, an arm depending from said table top frame and pivoted on the hinge connection between the table top support and the table top, the roller engaging edge of said depending arm terminating in a hook, said roller in rolling engagement on the roller engaging edge of said arm and said hook, said roller and depending arm together with its hook being in such relationship that when said piston moves outwardly carrying 60 said roller, that said table top will be rotated about its hinged connection with said table top support to a substantially vertical position.

2. In combination with a pedestal, a table top support, a table top hingedly secured to said table top support, means for elevating said table top support and rotating said table top on said table top support, which means comprises a hollow piston secured to said table top support and positioned in said pedestal in spaced relationship therewith, a motor, a pump, and a two-way valve mounted in said table top support, said motor so positioned as to operate said pump and said pump in fluid engagement with said two-way valve, an intake pipe extending from said pump into said 75 hollow piston, said piston in sliding engagement

in said pedestal, a pipe extending from and in fluid engagement with said two-way valve and terminating below and through the floor of said hollow piston, a cylinder, a second piston in sliding engagement in said cylinder formed on said table top support, a pipe connecting said two-way valve with the inner ends of the cylinder formed on said table top support, a pipe in fluid communication with said two-way valve and terminating in the space above said hollow piston, which in turn is in fluid communication with said hollow piston, an arm, a roller secured to said second piston so as to engage said arm secured to said table top and pivotally secured to said table top support so that when said second piston is moved outwardly said table top will be rotated about its pivotal connection with said table top support, a fluid positioned in said cylinder systems so that when said table is in its lowest position it may be raised by operating said motor and pump and forcing the fluid beneath said hollow cylinder to raise the piston in said hollow cylinder and so that when the table top support is in its lowest position that said table top may be rotated by actuating the motor and pump and forcing said fluid from the hollow pedestal through said two-way valve behind the second piston.

3. In combination with a table top, side frame members secured thereto, two standards mounted thereon, a cushion, said cushion pivotally secured to said standards, a knee flexer pivotally secured to said cushion, a pair of curved runners secured to the underside of said knee flexer, which runners of said knee flexer ride on the top surfaces of the side frame members of the table top, a jack mounted on the table top for raising and lowering the cushion, having its upper movable element in contact with the lower face of said cushion.

4. In combination with a pedestal, a table top support, a table top hingedly secured to said table top support, means for elevating said table top support and tilting said table top on said table top support, which means comprises a hollow piston positioned in said pedestal in spaced relationship, a pump, a motor and a two way valve mounted in said table top support, said motor so positioned as to operate said pump, said pump being in fluid communication with said two way valve, 50 an intake pipe extending from said pump into said hollow piston, said piston in sliding engagement in said pedestal, a pipe extending from and in fluid engagement with said two way valve and terminating below said hollow piston, a cylinder, 55 a second piston in sliding engagement in said cylinder formed on said table top support, a pipe connecting said two way valve with the inner ends of the cylinder formed on said table top support, a pipe in fluid communication with said two way valve, and terminating in the space above said hollow piston, which in turn is in fluid communication with said hollow piston, an arm secured to said table top and pivotally secured to said table top support, a roller secured to said second piston, so as to engage said arm, so that when said second piston is moved outwardly said table top will be rotated about its pivotal connection with said table top support, a fluid positioned in said cylinder systems so that when said table is in its lowest position it may be raised by the operation of said motor and pump to force the fluid beneath said hollow cylinder to raise the piston in said hollow cylinder, and so that when the table top support is in its lowest position 75

that said table top may be tilted by actuating said motor and pump and forcing said fluid from the hollow pedestal through said two way valve behind said second piston, side frame members 5 secured to said table top, two standards mounted thereon, a cushion, said cushion pivotally secured to said standards, a knee flexer pivotally secured to said cushion, a pair of curved runners secured to the inner side of said knee flexer, which runners 10 of said knee flexer ride on the top surfaces of the side frame members of the table top, a jack mounted on the table top for raising and lowering the cushion, said jack having its upper movable element in contact with the lower 15 face of said cushion.

5. In combination with a pedestal, a table top support, a table top hingedly secured to said table top support, means for elevating said table top support and tilting said table top on said table 20 top support, which means comprises a hollow piston positioned in said pedestal in spaced relationship, a pump, a motor and a two way valve mounted in said table top support, said motor so positioned as to operate said pump, said pump being in fluid communication with said two way 25 valve, an intake pipe extending from said pump into said hollow piston, said piston in sliding engagement in said pedestal, a pipe extending from and in fluid engagement with said two way 30 valve and terminating below said hollow piston, a cylinder, a second piston in sliding engagement in said cylinder formed on said table top support, a pipe connecting said two way valve with the inner ends of the cylinder formed on said 35 table top support, a pipe in fluid communication

with said two way valve, and terminating in the space above said hollow piston, which in turn is in fluid communication with said hollow piston, an arm secured to said table top and pivotally secured to said table top support, a roller 5 secured to said second piston, so as to engage said arm, so that when said second piston is moved outwardly said table top will be tilted about its pivotal connection with said table top support, a fluid positioned in said cylinder systems so that when said table is in its lowest position it may be raised by the operation of said 10 motor and pump to force the fluid beneath said hollow cylinder to raise the piston in said hollow cylinder, and so that when the table top support is in its lowest position that said table top may be rotated by actuating said motor and pump and forcing said fluid from the hollow pedestal through said two way valve behind said 15 second piston, side frame members secured to 20 said table top, two standards mounted thereon, a cushion, said cushion pivotally secured to said standards, a knee flexer pivotally secured to said cushion, a pair of curved runners secured to the inner side of said knee flexer, which runners of 25 said knee flexer ride on the top surfaces of the side frame members of the table top, a jack mounted on the table top for raising and lowering the cushion, said jack having its upper movable element in contact with the lower face of 30 said cushion, a rack bar secured to said table top, cushions mounted on said standards which are in operative engagement with said rack bar.

HENRY E. SAAK. 35
